UNITED STATES PATENT OFFICE.

LOUIS A. PFEIFFER, OF SAN FRANCISCO, CALIFORNIA.

OIL-FUEL HEATER.

1,400,179.

Specification of Letters Patent. Patented Dec. 13, 1921.

Application filed February 11, 1920. Serial No. 357,880.

To all whom it may concern:

Be it known that I, LOUIS A. PFEIFFER, a citizen of the United States, and a resident of the city and county of San Francisco, 5 State of California, have made a new and useful invention—to wit, Improvements in Oil-Fuel Heaters; and I do hereby declare the following to be a full, clear, concise, and exact description of the same.

10 The invention relates particularly to heaters for oil fuel and has for its object minimizing the possibilities of leakage by which oil fuel might become mixed with the heating steam or water. The invention includes 15 the construction and arrangement of parts whereby any leakage at joints must occur outside of the apparatus instead of interiorly as often occurs in present practice.

In this specification and the annexed 20 drawings the invention is illustrated in the form considered to be the best, but it is to be understood that the invention is not limited to such form, because it may be embodied in other forms, and it is also to be understood that in and by the claims 25 following the specification it is desired to cover the invention in whatever form it may be embodied.

In the accompanying one sheet of drawings:—

Figure 1 is a vertical section of a heater constructed in accordance with my invention.

Fig. 2 is a detail view of the strainer plug 35 for admitting oil to my heater.

In detail, the construction illustrated in the drawings includes a cylindrical oil chamber comprising the walls 1, closed at the top and bottom by the heads 2 and 3, preferably 40 concavo-convex for greater strength and integrally welded at their peripheral points of contact with the wall 1, to form a pressure tight oil drum. The head 2 is provided with a central spud to receive the threaded 45 nipple 4 through which the oil is introduced to the drum chamber. The bottom 3 of the drum is provided with a nipple 5 and the blow-off pipe 5' to provide means for introducing steam under pressure to the interior of the chamber for the purposes of 50 cleaning. Concentrically with the walls of the drum 1, I arrange the central stay tube 6 welded to the bottom 3 and the head 2 before they are introduced into the drum cylinder. The incoming oil is introduced 55

through this stay tube to the bottom of the drum, escaping through the notches 7 formed in the edges of the lower end of the tube. All of the welding herein referred to is at present accomplished by the use of the oxy-acetylene flame, but it may be accomplished by brazing or otherwise with the object of forming the heater and its assembled parts into an integral whole.

The drum 1 is surrounded by a steam 65 jacket formed by the cylindrical wall 8, having its upper and lower edges flanged in as at 9 and 10 to approximate contact with the outer surfaces of the drum 1 to which it is welded as described, to form a pressure tight 70 jacket 8' concentric with the drum 1. Surrounding this steam jacket is a concentric oil space, formed by the wall 11 having its ends 12 and 13 similarly flanged in and welded to the wall 8 to form a pressure tight oil jacket 75 11' surrounding the aforesaid steam space. A further steam jacket 14' is superimposed over the oil jacket by the wall 14 flanged in at 15 and 16 and joined to the wall 11 by welding as previously described. These 80 superimposed concentric walls are preferably made in graduated height to facilitate assembling and welding as illustrated in the drawing, contributing also to the symmetry and good appearance of the structure. The 85 heater rests upon the feet 17—17 suitably welded to the outer surface of the heater. Similar angular supports 18—18 are provided at the top of the heater to receive pumps or other machinery to be assembled 90 therewith.

The elbow 19 establishes communication between the oil drum and the oil jacket to which its respective ends are welded. Oil is delivered from the oil jacket through the 95 nipple 20 screwed thereinto. Steam is introduced into the inner and outer steam jackets through the inlets 21 and 22 respectively circulating therethrough and escaping, along with its condensation, to the outlet 100 23, communicating with the bottom of both jackets.

The oil is caused to take a serpentine path around and through the oil space 11' between the walls 8 and 11 because of the 105 fact that the shell 11 is formed with spiral corrugations 29 which contact with the shell 8 which is also spirally corrugated throughout its length. The shell 14 is also corrugated and all welded at their points 110

- of contact one with the other. This forms a spiral channel between the jackets causing the oil and steam to circulate around and around between the jackets before reaching the exits, in this manner preventing the oil taking a short circuit from the elbow 19 to the outlet 20, retaining it longer in the jacket and consequently raising its temperature to a higher degree.
- 10 By constructing the shell with spiral corrugations, a lighter material may be used, and at the same time a very rigid structure produced. The spiral corrugations also allow for a certain amount of expansion due to heat without injury to the device. These corrugations also form convenient means for welding one shell to another thereby producing spiral passages between. It will be noted that the oil enters the heating chamber 11' at the bottom and passes upwardly while the steam enters the spiral passages surrounding the oil passage at the top and proceeds to the bottom thereby causing the fluids to flow in opposite directions, which results in the oil in its hottest condition coming in contact with the heated steam entering the steam passages. It is obvious that the oil will leave the heater in its hottest possible condition by this arrangement of parts.
- The invention operates substantially as follows:—The oil to be heated is pumped through the supply pipe 31 into the passage 32 in the plug 33, passes through the strainer 34 into the outlet passage 35 of the strainer. The plug 33 is operated by the handle 36 in the usual manner. From the passage 35 the oil flows through the pipe 37, through the nipple 4 and into the tube 6 in the oil drum, from which it passes as previously described. When the handle 36 is turned at an angle of 90 degrees from the position shown, the by-pass 38 connects across the supply pipe 31 to the pipe 37 cutting out the strainer, which may be thoroughly cleaned by admitting steam into the chamber 35 blowing off the accumulations from the interior of the strainer 34 which drain off through the cock 39.
- 50 Having thus described this invention what I claim as new and desire to secure by Letters Patent of the United States is as follows:—
1. A heater including a drum, a plurality of spaced walls surrounding said drum and joined thereto and to each other at the ends thereof, each of said walls being provided with spirally projecting shoulders thereon, so that the shoulders of the first wall adjacent the drum will contact therewith to form a spiral passage and the shoulders of the remaining walls contact with the next adjacent walls, intermediate the shoulders thereof, to form spiral passages.
  - 65 2. A heater including a drum, a series of

superimposed spirally corrugated walls surrounding said drum and having their ends flanged in and welded to the contiguous walls and the drum wall respectively.

3. A heater including a series of spirally corrugated walls surrounding a drum, said walls so joined to each other and the drum that all said joints are outside of said heater.

4. A heater including a drum, a plurality of spirally corrugated walls of graduated lengths surrounding said drum and joined thereto and to each other, whereby all of said joints are exterior.

5. A heater including a drum having an inlet, an annular wall surrounding said drum and having its edges welded thereto, an annular wall surrounding said annular wall and having its edges welded thereto to form an oil jacket, having an outlet and a passage connected with said drum.

6. A heater including a drum, a wall surrounding said drum and joined thereto, a second wall surrounding said first mentioned wall and joined thereto, and a spiral corrugation formed in each of said walls.

7. A heater including a drum having an oil inlet, a steam jacket formed by a spirally corrugated wall surrounding and joined to said drum, an oil jacket formed by a spirally corrugated wall surrounding and joined to the wall of said steam jacket, and connected with said drum and having an outlet, a second steam jacket formed by a spirally corrugated wall surrounding and joined to the wall of said oil jacket, and means for passing steam through said steam jackets.

8. A heater including a drum having an oil inlet, a steam jacket formed by a spirally corrugated wall surrounding and joined to said drum, an oil jacket formed by a spirally corrugated wall surrounding and joined to the wall of said steam jacket, and connected with said drum and having an outlet, a second steam jacket formed by a spirally corrugated wall surrounding and joined to the wall of said oil jacket, and means for passing fluid through said jackets.

9. A heater including a drum having a central tube extending throughout its length and having lateral openings adjacent to the end of said drum, and an inlet to said drum within said tube, a steam jacket formed by a spirally corrugated wall surrounding and joined to said drum, an oil jacket formed by a spirally corrugated wall surrounding and joined to the wall of said steam jacket, and connected with said drum and having an outlet; a second steam jacket formed by a spirally corrugated wall surrounding and joined to the wall of said oil jacket; and means for passing steam through said steam jackets.

10. A heater including a drum having an

- oil inlet; a steam jacket formed by a wall surrounding and joined to said drum, an oil jacket formed by a wall surrounding and joined to the wall of said steam jacket, and connected with said drum and having an outlet; a second steam jacket formed by a wall surrounding and joined to the wall of said oil jacket; and means for causing steam and oil to circulate spirally through their respective jackets in opposite directions to each other.
11. A heater including a drum, a plurality of spaced walls surrounding said drum and joined thereto and to each other at the ends thereof, each of said walls being provided with spirally projecting shoulders thereon so that the shoulders of one wall contact with the next adjacent wall intermediate its shoulders.
12. A heater including a drum, a wall surrounding said drum and joined thereto at its ends; a plurality of spaced walls surrounding said first mentioned wall, each of

said walls being joined to each other at their ends and spiral shoulders formed in each of said walls contacting with the adjacent surrounded wall to form a plurality of spiral passages.

13. A heater including a drum having an oil inlet; a steam jacket, formed by a wall having spirally projecting shoulders thereon, surrounding and joined to said drum; an oil jacket, formed by a wall having spirally projecting shoulders thereon, surrounding and joined to the wall of said steam jacket and connected with said drum and having an outlet and a second steam jacket, formed by a wall having spirally projecting shoulders thereon, surrounding and joined to the wall of said oil jacket and means for passing steam through said jackets.

In testimony whereof, I have hereunto set my hand at San Francisco, Cal., this 31st day of January, 1920.

LOUIS A. PFEIFFER.
